Certificate of Correction.

It is hereby certified that Design Letters Patent No. 68,357, granted September 29, 1925, upon the application of James Swanson, of Chicago, Illinois, for an improvement in "A Mail Box," were erroneously issued for the term of "fourteen years," whereas said Letters Patent should have been issued for the term of seven years; and that the said Letters Patent should be read with this correction therein that the same may conform to the record of the case in the Patent Office.

Signed and sealed this 10th day of November, A. D. 1925.

Acting Commissioner of Patents.

UNITED STATES PATENT OFFICE.

JAMES SWANSON, OF CHICAGO, ILLINOIS.

DESIGN FOR A MAIL BOX.

Application filed July 20, 1925. Serial No. 14,147. Term of patent 14 years.

To all whom it may concern:

Be it known that I, JAMES SWANSON, a citizen of the United States, residing at Chicago, in the county of Cook and State of Illinois, have invented a new, original, and ornamental Design for Mail Box, of which the following is a specification, reference being had to the accompanying drawing, forming a part thereof.

Fig. 1 is a top plan view;

Fig. 2 is a front view; and

Fig. 3 is a side view of the mail box showing my new design.

I claim:—

The ornamental design for a mail box, as shown.
